UNITED STATES PATENT OFFICE

EDMUND C. MORGAN, OF NEW YORK, N. Y.; OLIVE EUGENIE MORGAN EXECUTRIX OF
SAID EDMUND C. MORGAN, DECEASED

LOADING MACHINE

Application filed August 14, 1917, Serial No. 186,118. Renewed December 7, 1922.

This invention relates to machines for loading coal and other material either in the mine or on the surface of the earth, and has for its object the provision of a machine of the class named which shall be of improved construction and more efficient, economical and convenient in operation than similar devices previously known.

The invention is exemplified in the combination and arrangement of parts shown in the accompanying drawings and described in the following specification, and it is more particularly pointed out in the appended claims.

In the drawings, Fig. 1 is a top plan view of one form of machine embodying the present invention, in position in a mine chamber.

Fig. 2 is a side elevation of the machine shown in Fig. 1,

Fig. 3 is a side elevation on an enlarged scale of the rear portion of the machine shown in Figs. 1 and 2,

Fig. 4 is a side elevation of the central portion of the same machine,

Fig. 5 is a side elevation of the front portion of the same machine,

Fig. 6 is a vertical sectional view on line 6—6 of Fig. 5,

Fig. 7 is a top plan view of the rear portion of the machine,

Fig. 8 is a top plan view of the central portion of the machine,

Fig. 9 is a top plan view of the front portion of the machine,

Fig. 10 is a top plan view of the rear truck by which the machine is supported, with the conveyer mechanism removed therefrom,

Fig. 11 is a top plan view of the front portion of the machine with the conveyer removed therefrom and with the supports for the conveyer in section,

Fig. 12 is a vertical sectional view substantially on line 12—12 of Fig. 2,

Fig. 13 is a rear elevation of the machine,

Fig. 14 is a top plan view of the rear portion of a modified gathering device for receiving material to be loaded,

Fig. 15 is a side elevation of the parts shown in Fig. 14,

Fig. 16 is a top plan view of the front

portion of the attachment shown in Fig. 14, Fig. 17 is a side elevation of the part shown in Fig. 16,

Fig. 18 is a fragmentary side elevation of a detail of construction,

Fig. 19 is a top plan view with parts in section, of the device shown in Fig. 18,

Fig. 20 is a perspective view showing the attaching means for the cable by which the machine is shifted,

Fig. 21 is a vertical sectional view of the attaching means shown in Fig. 20, and

Fig. 22 is a vertical sectional view on line 22—22 of Fig. 21.

The general construction of the machine selected for illustrating the invention is shown in Figs. 1 and 2. As will be seen in these figures, a forward truck A and a rear truck B have their adjacent ends connected with one another and carry a forward conveyer section C and a rear conveyer section D which are similarly connected to one another. The forward conveyer section may be swung laterally, as shown by broken lines in Fig. 1, and may also be swung vertically as shown by broken lines in Fig. 2. The normal position of the forward section C for receiving material is that shown in full lines in Fig. 2 with the bottom of the conveyer resting upon the surface from which the material is received.

As shown best in Figs. 4, 5, 11 and 12, the forward truck is provided with a main frame 1 having side pieces 2 and 3 which have their lower edges connected with a bottom plate 4. Wheels 5 are carried on front and rear axles 6 and 7 respectively which are journaled in the side members 2 and 3 of the truck frame. The side members 2 and 3 extend rearwardly to form a frame ring 8 by which the forward truck is connected with the rear truck, as will be more fully explained. A plate or web 9 is connected with the bottom portion of the frame ring 8 and forms a platform extending over the entire surface closed by the ring. Brackets 10 are secured to the side piece 2 and support a platform 11 having a hinged extension 12 on which the operator stands. A motor 13 is provided with supporting collars 14 which surround the shaft 6 and hold

the motor in driving connection therewith. A gear 15 is secured to the shaft 6 and meshes with a pinion 16 carried on the armature shaft of the motor. A bolt or rod 17 extends upwardly from the base plate 4 of the truck frame and carries coil springs 18, Fig. 4, for supporting the motor frame in the well known manner.

A pair of relatively heavy lever bars 19 are fulcrumed on the forward axle 6 of the truck A and are provided with arcuate racks 20 by which they may be rotated about the axle 6. Pinions 21, carried on the shaft 22, mesh with the racks 20 and are in turn driven by a motor 23 through worm gearing 24, pinion 25 and gear 26 which is secured to the shaft 22. The worm 24 is secured to the armature shaft of the motor 23 and meshes with a worm wheel 27 carried on a jack shaft 28 mounted in bearings 29 supported by brackets 30 secured to the casing of the motor 23. It is apparent that rotation of the motor 23 will rock levers 19 about the axle 6 with a slow powerful movement and that the levers will be held in any position to which they are moved by the worm 24 and worm wheel 27. The forward ends of the levers 19 carry a web plate 31 which has its forward edge provided with a heavy arcuate rib or bead 32, shown best in Figs. 5 and 11. The web 31 and the bead 32 both extend to a considerable distance on either side of the levers 19. Supporting brackets 33 extend downwardly at the outer edges of the web 31 a sufficient distance to rest upon the surface of the earth when the forward ends of the levers 19 are in their lowermost position, as shown in Fig. 5.

The front conveyer section C is carried by the forward truck A and has a front and rear bearing upon the truck. The front portion of the conveyer frame, as shown in Fig. 5, is provided with an arcuate notch 34 which receives the rib 32 of the lever bars 19 so that the front portion of the conveyer may be raised or lowered as the lever bars are tilted about the axle 6. The rear end of the conveyer C, as shown best in Fig. 8, is pivotally mounted on a shaft 36 carried in a yoke 37 which is provided with a slide support 38 resting upon an arcuate slideway 39 formed on the upper ends of standards 40 which project upwardly from the main frame 1 of the truck. When the conveyer section C is raised or lowered it moves about the shaft 36 as an axis. The yoke 37 extends rearwardly, as shown in Figs. 4 and 8, and is pivotally connected by a pin 41 to a complimentary yoke 42 connected with the conveyer section D. The bearing slides 38 and 39 are curved about the axis of the pin 41 as a center so that the conveyer section C may be swung from side to side about the pin 41 as an axis.

Lateral swinging of the conveyer section C is effected by a motor 45, Fig. 11, mounted on a plate 46 supported between the lever bars

19. The motor 45 provides a worm 47 which meshes with a worm wheel 48 secured to an upright shaft 49 journaled in a vertical bearing in the plate 46 and carrying a drum secured to its lower end beneath the plate. A pair of cables 51 and 52 have their ends secured to this drum and pass around pulleys 53 and 54 respectively journaled at the opposite edges of the plate 31. The cables 51 and 52 are carried backwardly from their respective pulleys and connected to lugs 55 and 56 formed on the frame of the conveyer C, a portion of which is shown in broken lines in Fig. 11. It is apparent that by this arrangement, rotation of the motor 45 in one direction will shift the conveyer section C to the left, while rotation of the motor in the opposite direction will shift the conveyer to the right. During this shifting movement the arcuate notch 34 in the conveyer frame slides upon its supporting rib 32.

The conveyer section C, as shown in Fig. 12, is made up of a lower bed plate 57 which is bent upwardly to form side walls 58 and rebent downwardly and inwardly to form inclined plates 59 which carry horizontal flanges 60 at their lower edges. An upper bed plate 61 is secured to the side walls 58 and is spaced a sufficient distance above the plate 57 to form a casing for the lower run of the conveyer 62 which is made up of chains 63 and cross slats or flights 64. The upper plate 61 is secured to the sides 58 by angle bars 65 and is also connected to the flanges 60 by angle bars 66. The front end of the conveyer C, as shown in Figs. 5 and 6, is provided with a detachable section E which forms a scoop for receiving material to be loaded. This section, as shown best in Fig. 9, has its side walls extended laterally and is provided at its front end with a shoe 67 which may be forced beneath the material to be loaded. A roller 68 is journaled in the shoe 67 and the forward ends of the conveyer chains 63 pass around this roller. The scoop section E is provided with a suitable framework 69 which is secured to the main portion of the conveyer section C by means of bolts 70. The frame 69 is so shaped that its lower surface rests squarely upon the surface of the ground when the conveyer is tilted downwardly, as shown in Fig. 5, thus forming a bearing for supporting the front end of the conveyer upon the surface from which the material is received. The chain conveyer 63 at its rear end, passes over a roller on the shaft 36, as shown in Fig. 4. The lower runs of the chains pass over sprockets 71 which are secured to a shaft 72 rotatively mounted in bearings carried by the conveyer frame. The shaft 72 is driven from a motor 73 also suspended from the conveyer frame through connecting gears 74. By this means the conveyer is driven to elevate the material received in the forward end of the conveyer section, and to discharge the

material from the upper rear end into the conveyer section D.

The rear truck B, as shown best in Figs. 3, 4, 10 and 13, is provided with a main frame similar to that of the forward truck which has side members 75 and 76 which have forwardly projecting arcuate extensions 77 and 78 respectively, which partially encircle the frame ring 8 of the forward truck A. The rear truck frame is centrally parted and is secured together by lugs 79 and bolts 80 and by an elongated bolt 81 at the rear end of the frame. This permits the extensions 77 and 78 to be assembled in place about the frame ring 8 of the forward truck. The rear truck frame is provided with a bed plate 82, similar to the bed plate 4 of the forward truck but parted along its center as previously stated. Wheels 83 are secured to axles 84 and 85 journaled in the frame members 75 and 76, and the forward axle 84 is driven by a motor 87 provided with a pinion 88 which meshes with a gear 89 secured to the axle 84. A shaft 90 is journaled in bearings 91 and 92 formed in the side members 75 and 76 respectively, and this shaft carries a series of drums 93, 94, 95 and 96. The shaft is driven from a motor 97 secured to the bed plate 82 of the truck frame and provided with reduction gearing 98 by means of which it is connected with the shaft 90. As shown in Figs. 4, 11 and 19, the circular frame ring 8 is provided with an outwardly extending flange or tongue 100 which is received by a groove or recess 101 formed by overlying flanges 102 on the arcuate extension 77 and 78 of the rear frame. By this arrangement it is apparent that the frames of the two trucks are rigidly held from vertical movement relative to one another but are free to swing in a horizontal direction about the center of the frame ring 8 as a pivot. As shown in Figs. 18 and 19, the frame ring 8 is provided with a series of openings 103 which receive a pin or bolt 104 carried by the extension 78 of the rear truck frame. The bolt 104 is pressed inwardly by a spring 105 carried in a housing 106 secured to the extension 78, but may be held in withdrawn or retracted position by placing the bent end 107 of the bolt in position to rest upon the stop 108 carried by the housing 106. A number of holes 103 is provided so that the two trucks may be locked in various angular positions relative to one another.

The rear conveyer section D is provided at its forward or receiving end with a hopper 110 which is pivotally secured to the circular web 9 of the frame ring 8 of the main truck by means of a pivot pin 111. The hopper 110 has its forward portion positioned to receive material discharged from the front conveyer section C. The conveyer is provided, adjacent the rear portion of the truck B, with brackets 112, Figs. 3 and 13, which have rollers 113 journaled thereon and arranged to

travel on an arcuate track 114 supported on upwardly projecting lugs 115 carried by the main frame of the truck. The brackets 112 also support a motor 116 which drives a shaft 117 carrying sprocket wheels 118 arranged to engage the lower run of the conveyer chains 119 which are provided with flights 120 for moving the material over the rear conveyer D. The conveyer section D is provided with a vertically swinging extension 121 pivotally secured to the main portion of the conveyer at 122 and provided with forwardly extending arms 123 which are pivotally connected at 124 with threaded rods 125 which pass through openings in lugs 126 secured to the sides of the conveyer frame. Coil springs 127 surround the ends of the rods 125 beneath the lugs 126 and rest upon the upper surface of hand wheels 128 which engage the threads on the rods 125 and by means of which the tension of the springs 127 may be adjusted to raise or lower the rear end of the adjustable conveyer section.

It should be noted that by locating the driving sprocket wheels 118 in front of the position which the mine car 129 assumes under the overhanging portion 121 of the conveyer, the chains 119 are drawn taut so as to prevent them from sagging down against the forward wall of the mine car. This feature of my invention is shown in Figs. 32 to 34 inclusive, of my co-pending application, Serial No. 569,167, filed June 27, 1910, renewed August 4, 1915, renewal Serial No. 43,696, for an improvement in mining machines. It will also be seen by referring to Fig. 3 of applicant's drawings, that the pivotal point 122 of the overhanging portion 121 of the conveyer is directly above the axis of the sprocket wheels 118, which arrangement enables the overhanging portion 121 of the conveyer to be tilted up or down without interfering with the feature of the sprocket wheels 118 holding the conveyer chains 119 taut until they extend forwardly beyond the sprocket wheels 118. Therefore the pivoted section 121 may be inclined upwardly or downwardly to a considerable extent with the assurance that the conveyer will never sag unduly and have its movement interfered with by any part of a mine car, material already loaded, or by other objects. This relation of a pivoted sectional overhanging conveyer and driving sprocket wheels with their axes in the same vertical plane as the pivot of the overhanging portion of the conveyer is shown in Fig. 49 of my co-pending application, Serial No. 671,601, filed January 17, 1912, for an improvement in mining machines.

The forward ends of the conveyer chains 119 pass over rollers carried on a shaft 128 journaled in the bottom of the hopper 110 in position to move material in the hopper upwardly and rearwardly along the conveyer

section D and to finally discharge the material from the rear end of the conveyer. Any suitable form of transport such as a car, shown at 129 in Fig. 3, may be provided for 5 receiving the material and transferring it to any desired locality. The conveyer section D is provided with upper and lower bed plates for the different runs of the conveyer as shown in Fig. 13, the construction being similar to that described in connection with the conveyer section C.

A series of controllers 130 are mounted on the yoke 37 which carries the forward conveyer section C in a position adjacent the operator's platform 12. These controllers govern the various motors which drive the different parts of the machine, but separate controllers need not be provided for the two traction motors 13 and 87, since these motors operate in unison with one another and may be governed by a single controller. A supplementary controller 131, for the motor 116 which drives the rear conveyer, is preferably mounted on the rear portion of this conveyer 25 and connected in parallel with the controller 130 for this motor so that the rear conveyer may be governed either from the operator's position or from the car 129.

For shifting the machine forwardly or rearwardly during loading operations, forwardly extending cables 132 are secured to the drums 93 and 96, and rearwardly extending cables 133 are secured to the drums 94 and 95. The ends of the cables 132 are attached at 134, Fig. 9, to wall jacks 135 having their inner ends pivoted together at 136 and having their outer ends pivoted to blocks 137 arranged to bear against the walls of the mine chamber. The inner ends of the wall 40 jacks 135 are inclined forwardly so as to form a toggle to force the jacks into contact with the walls of the chamber and prevent rearward movement. The cables 133 have their outer ends secured, as shown in Fig. 10, 45 to holding arms 138 of a clamping device arranged to engage the rails of the track upon which the machine runs. It will be apparent that when the motor 97 is driven in one direction, the cables 132 will be wound 50 upon their drums while the cables 133 will be paid out and the machine will be moved forwardly. When the motor is driven in the opposite direction, a reverse operation will take place.

55 By having the pivots 41 and 111 in vertical alinement with each other so that the vertical axis between the trucks is coincident with the axis between the rear loading conveyer D and the forward conveyer C, operation of the loading machine on curved portions of a mine track will be greatly facilitated.

The clamp for holding the ends of the cables 133 is best shown in Figs. 20, 21 and 60 22 and is described and claimed in my co-

pending divisional application Serial No. 305,748, filed September 13, 1928, for rail clamps for loading machines. This clamp comprises a shaft 140 with which the arm 138 is integral. Adjacent the arm 138 the shaft is provided with a circular portion 141 on which a jaw 142 is journaled. On the side of the jaw opposite the arm 138 the shaft is provided with an eccentric portion and beyond the eccentric portion a second circular portion 144, co-axial with the portion 141, is provided. A second jaw 145 is journaled on the portion 144, and adjacent the outer face of the jaw a U-shaped retainer 146 is placed. The legs of the U-shaped retainer 146 are 70 provided with inwardly projecting ribs 147 which enter slots 148 in the sides of the circular portion 144 when the legs of the U-shaped retainer are slid into place. When it is desired to secure the clamp in position 75 on a rail, the retainer 146 and the jaw 145 are removed from the end of the shaft 140 and the shaft inserted beneath the rail so as to bring the jaw 142 into engagement with the upper surface of the lower rail flange 80 and the eccentric portion 143 into engagement with the lower surface of the flange. The jaw 145 and the retainer 146 may then be replaced and when this is done any forward tension upon the cable 133 will cause 85 the lower rail flange to be clamped between the two jaws and the eccentric 143, and thus the device will be firmly held in position and the greater the tension upon the cable, the stronger will be the grip upon the rail. To 90 release the clamp, it is only necessary to move the arm 138 backwardly a slight distance after which the clamp may be shifted along the rail, or the retainer 146 may be removed and the clamp placed in a new position.

In Figs. 14 to 17 inclusive, there is shown an alternative receiving portion which may be substituted for the portion E of the forward conveyer section C shown in Fig. 5. This substitute receiver is provided with a frame 150 corresponding to the frame 69 of the conveyer section E and arranged to be secured to the conveyer section C by the bolts 70. The frame 150 carries a hopper 151 which has a downwardly extending circular slideway 152 arranged to receive a sliding ring 153 which is connected with a second section 154 having its forward end shaped like the receiving end of the section E and provided with a shoe 155, Figs. 16 and 17, 100 which may be forced beneath material to be loaded. The frame 150 carries a roller 156 within the hopper 151 over which roller the conveyer chains 63 pass. Supported by the frame 150 in the space beneath the conveyer 105 63 is a motor 157 which drives a drum 158 by means of worm gearing 159. A cable 160 is given one or two turns about the drum 158 and has its ends secured to lugs 161 projecting from the outer periphery of the slide ring 110

153. By driving the motor 157, the conveyer section 154 may be shifted to either side of the hopper 151 so that the receiving section 154 may be directed laterally relative to the main portion of the conveyer. When the receiving section 154 is so directed, the main portion C of the conveyer may be swung sidewise upon its support to force the shoe 155 beneath the material and thus the device may be made to pick up material by sidewise movement, thus materially extending the field of operation of the loading machine relative to the track upon which it is carried. The receiving portion 154 is provided with a conveyer 162 which is driven by a motor 163 through gearing 164 and sprocket wheels 165. The conveyer 162 is arranged to discharge into the hopper 151 for all positions of the receiving section.

20 In operation current is supplied to the machine in any well known manner and the device is moved to the point where loading is to be carried on by means of the two driving motors 13 and 87, the machine traveling upon a track which has been previously laid to a point adjacent the material to be loaded. During this transportation, the forward conveyer C is supported in an elevated position, as shown in broken lines in Fig. 2, and the weight of the conveyer is carried by the front truck. During such transportation also the catch 104 may be withdrawn to permit shifting of the two trucks relative to one another so that the machine may pass readily around 25 comparatively sharp turns in the track. After the machine has thus been brought to the scene of operation, the wall jacks 135 are placed in position and the cables 132 secured to them. In like manner, the clamps 138 are secured to the rails in the rear of the machine and the cables 133 fastened to the clamps. The conveyer section is now lowered until its bottom surface rests upon the surface upon which the material to be loaded is supported 40 and the drums 93 and 96 are driven to move the machine forwardly and force the shoe 65 beneath the material. During this movement, the conveyer sections C and D are operated to carry the material rearwardly and 45 discharge it into the car 129. The conveyer section C is not limited to the field immediately in front of the machine but the section may be swung to either side, as shown in Fig. 1, and thus pick up the material from a considerable range. If a still greater lateral 50 range is desired, the supplementary receiving section, shown in Figs. 14 to 17, may be substituted for the section E and the material caused to enter the conveyer by sidewise movement while the receiving section is set at 55 an angle to the principal axis of the machine.

It should be noted that the forward movement of the machine by which the conveyer is forced beneath the material to be loaded, is 60 not limited by the position of the forward

truck A upon the track, but the machine may be moved forwardly until this truck is carried entirely beyond the end of the track. When the machine is in this position, the weight of the front conveyer rests upon the 70 surface of the earth itself and the front truck is held in rigid position relative to the rear by means of the interfitting rings by which they are connected to one another. The forward ends of the levers 19 which rest in the groove 34, aid in supporting the weight of the front truck A. The ribbed end of the levers 19, resting in the groove 34, positively holds the forward end of the conveyer downwardly upon the surface from which the material is being removed and prevents the conveyer from riding over the material. When the conveyer is swung to one side or the other, the weight of the truck is transmitted 75 to the supporting surface by the downwardly 80 projecting legs 33 carried by the levers 19, and thus any tendency of the machine to tip is overcome. The machine may thus be operated a very considerable distance in advance 85 of the track, the only requirement being that 90 the rear truck shall remain upon the track.

The discharge conveyer D may be moved manually from side to side to distribute the load in the transporting car, the hopper at the forward end of the conveyer remaining 95 always in position to receive the material from the forward conveyer and since the forward conveyer swings from side to side about the same axis as the rear conveyer, it will always be in position to discharge into the 100 hopper. The two conveyers have the same pivotal axis as that of the two trucks so that during transportation the entire machine has a single pivotal axis at its central portion to 105 permit easy turning about sharp corners. While the machine is being transported, the operator's platform 12 may be swung upwardly so that the machine may pass easily 110 through narrow chambers or between mine props, such as are shown at 165 in the drawings.

I claim:

1. In a loading machine, the combination with two pivotally connected trucks each provided with wheels adapted to travel on a mine track, and conveyer mechanism carried by said trucks and comprising sections pivotally connected directly to each other to swing relatively to each other and each relatively to said trucks on an upright axis coinciding with the pivotal axis between said trucks.

2. In a loading machine, the combination with two trucks pivotally connected together to swing relatively to each other on an upright axis with each truck provided with wheels adapted to travel on a mine track, of conveyer mechanism carried by said trucks and comprising sections pivotally connected above the pivotal connection between the trucks and arranged to swing about said up-

right axis, and a hopper in position to maintain delivery communication between the conveyer sections about said upright axis for the various positions of the conveyer sections relative to each other.

5. 3. In a loading machine, the combination with a truck provided with wheels adapted to travel on a mine track, of a discharge conveyer mounted on said truck and provided 10 with a deep storage hopper at its forward end in position for receiving material, means for supporting said discharge conveyer together with said storage hopper on said truck to swing about an upright axis extending 15 through said hopper, an additional truck also provided with wheels adapted to travel on said mine track, an additional conveyer mounted on said additional truck in position to deliver material to said storage hopper, 20 means for operating said additional conveyer to deliver material to said storage hopper, and means for operating said discharge conveyer to remove the material from said storage hopper and transfer it to a mine car on 25 said track.

4. In a loading machine, a supporting truck, a conveyer having its discharge end extending in the rear of said truck, a motor for operating said conveyer, a controller for 30 said motor located on said truck, and a second controller for said motor located adjacent the discharge end of said conveyer.

5. In loading machine, the combination with a conveyer having a discharge section 35 pivoted to swing on a horizontal axis, of an arm connected to said discharge section and extending forwardly at one side of said conveyer, resilient mechanism connected between said arm and said conveyer at one side 40 thereof, and means for adjusting the elevation of said arm to adjust the position of the discharge end of said discharge section about said horizontal axis.

6. In a loading machine, the combination 45 with a truck adapted to travel on a mine track, of a conveyer mounted on said truck and extending in advance thereof, means for adjusting said conveyer relative to said truck to support said conveyer clear of said track 50 during transportation along said track and for adjusting said conveyer downwardly for movement over a mine floor in advance of said track, and connections between said truck and said conveyer comprising a supporting ledge on the latter to transfer a portion of the weight of said truck to said ledge independently of said track to hold the truck off the ground in advance of the track and in position for movement back onto the track.

60 7. In a loading machine, material-handling mechanism comprising a forwardly projecting frame forming a scoop for receiving material, a truck for supporting said frame, and a lever mounted on said truck and having one end arranged to fit into a notch in said frame

so that said frame and truck are positively held by said lever from vertical movement relative to one another.

8. In a loading machine, material-handling mechanism comprising a forwardly projecting material-receiving frame, a truck for supporting said frame, means for shifting said frame about a vertical axis relative to said truck, and a lever carried by said truck for shifting said frame vertically, said lever having a bearing rib arranged to fit into a groove in said frame to hold said frame in fixed position vertically relative to said truck but to permit lateral movement of said frame about its vertical axis.

75 9. In a loading machine, material-handling mechanism comprising front and rear sections pivoted together for movement about a vertical axis, a pair of trucks for carrying said mechanism arranged one in front of the other and pivotally connected for horizontal movement about the same vertical axis, means for pivotally supporting said sections on said trucks each for lateral adjustment relative to said trucks, and means for locking said trucks in adjusted positions against movement about 85 said vertical axis.

10. In a loading machine, the combination with material-handling mechanism comprising a forward section and a rear section, of 95 a pair of trucks one for supporting the forward section of said material-handling mechanism and the other for supporting the rear section thereof, propelling mechanism comprising a motor on the forward truck, additional propelling mechanism comprising an additional motor on the rear truck, means for supporting the forward section of said material-handling mechanism for operation on a mine floor in advance of the mine track 100 on which said trucks are adapted to travel, and additional propelling mechanism for moving the forward truck along the track to effect operation of the forward section of said material-handling mechanism to gather 110 a load of material from the floor in advance of said track for transfer to the rear section of said material-handling mechanism.

11. In a loading machine, the combination with material-handling mechanism comprising a forward section having gathering means and a rear section having a deep receiving storage hopper, of spaced-apart trucks one for supporting the forward section of said material-handling mechanism and the other for supporting the rear section thereof, propelling mechanism connected to the wheels of the forward truck and comprising a motor mounted on the latter, additional propelling mechanism connected to the 115 wheels of the rear truck and comprising a motor mounted on the latter, and auxiliary propelling mechanism for the forward truck to force said gathering means into loose material on the floor in advance of the track 120 125 130

on which the trucks are adapted to travel to secure a load for transfer to said storage hopper.

12. In a loading machine, the combination with a supporting frame, of a conveyer mounted thereon to swing laterally relatively thereto, gathering means connected to the forward end of said conveyer and adjustable independently to various angular positions relative to said conveyer, means for moving said conveyer in the direction of the length thereof when said gathering means is in alinement therewith, and means for moving said conveyer transversely of the length thereof when said gathering means is adjusted to an angular position to receive material from the direction in which it is moved laterally.

13. In a loading machine, the combination with a supporting frame, of a conveyer mounted thereon to extend to the floor, a receiving section pivoted to the forward end of said conveyer at the floor, means for swinging said receiving section horizontally along the floor into various angular positions relative to said conveyer, and means for moving said receiving section along the floor to receive material from the directions corresponding to the respective positions of such receiving section.

14. In a loading machine, a conveyer for transferring material to be loaded having one end arranged to rest upon the surface on which the material rests, a receiving hopper connected with said end, a gathering section comprising a scoop and a receiving conveyer, said section being pivoted to said end and arranged to swing horizontally into different angles relative to said conveyer and to discharge into said hopper in its various positions, power mechanism for swinging said gathering section about its pivot, and means for moving said conveyer in different directions for forcing said scoop under the material to be loaded.

15. In a loading machine, a conveyer for transferring material to be loaded, means for moving said conveyer into and out of contact with the surface on which material rests, a receiving section connected on an upright axis to the forward end of said conveyer and having supplementary conveyer mechanism carried thereby, power mechanism for shifting said receiver section horizontally into various angular positions relative to said main conveyer, and power mechanism for driving the supplementary conveyer mechanism carried by said receiver section.

16. In a loading machine, the combination with a truck, of a forwardly extending conveyer mounted thereon, a receiving section at the forward end of said conveyer adjustable to various angular positions relative to said conveyer to receive material from different directions, means for moving the truck to

force said receiving section into contact with material to be loaded while said receiving section extends forwardly, and means for moving said conveyer laterally relatively to said truck when said receiving section is adjusted to a laterally extending position to cause said receiving section to gather material.

17. In a loading machine, the combination with a supporting frame, of a conveyer projecting forwardly therefrom and mounted thereon to swing laterally relatively thereto, a gathering conveyer adjustably mounted at the outer end of said first-named conveyer for adjustment in alinement with the latter and to extend transversely thereof in both directions, means for moving said supporting frame longitudinally of said conveyers when the latter are in alinement with each other, and means for swinging said conveyers laterally relatively to said supporting frame when said gathering conveyer is adjusted to a position extending laterally in either direction from the forward end of said first-named conveyer.

18. In combination with a loading machine comprising a truck with material handling mechanism supported thereon, of a pair of arms at the front of the truck and each including a member pivoted to the truck, and having an inner upright portion and a forwardly extending portion, means connected to the forwardly extending portions in position to engage the ground forwardly of the truck and assist in supporting the loading machine during the operation thereof, and self-contained power-operated mechanism connected to said inner portion to elevate said ground engaging portions.

19. In combination with a loading machine comprising a truck with material handling mechanism supported thereon, of a pair of spaced-apart arms at the front of the truck, said arms being pivoted to the truck, each arm comprising an inner upright portion and a forwardly extending portion, means connected to the forwardly extending portion in position to engage the ground forwardly of the truck, and means engaging the inner upright portion to adjust the elevation of the said arms and of the said ground-engaging means.

20. In a loading machine, the combination with two trucks, of arcuate tongue and groove connections between said trucks, a receiving conveyor for the forward truck, a loading conveyor for the rear truck, and a storage hopper of considerable depth and located at the said tongue and groove connection to maintain delivery communication thereto from the receiving conveyor at the various relative angular positions of the latter with respect to said loading conveyor.

21. In a loading machine, a frame, a superstructure mounted thereon to swing hori-

zontally and including an operating gathering member, means comprising arms for supporting the machine and connected to the forward part thereof and including low-lying ground-engaging mechanism over which said gathering member may be swung.

22. In a loading machine, a truck frame, a superstructure mounted thereon to swing horizontally and including a gathering member, means for supporting the machine while in operation comprising arms connected to the forward portion of the frame, means connected to the said arms in position to have a low-lying forwardly projecting ground engaging position, said arms being located beneath the superstructure so that the latter may be swung over the same.

23. A loading machine comprising a truck frame, a superstructure mounted thereon to swing laterally, and having a member adapted to scoop material from the floor in advance of the machine, means for supporting said member from the machine while in operation comprising arms connected to the truck frame and in position to slidably support said superstructure, and means connected to said arms to extend forwardly beyond the truck frame in position to engage the ground and assist in supporting the machine.

24. In a loading machine of the character described, the combination with a front and a rear truck pivotally connected to each other, a gathering conveyer pivoted upon the front truck to sweep horizontally back and forth, and a loading conveyer pivoted for lateral swinging movement upon the rear truck, the pivotal mounting of the gathering conveyer, the pivotal connection between the trucks, and the pivotal mounting of the loading conveyer being substantially coincident.

40 In testimony whereof I have signed my name to this specification, on this 13th day of August, A. D. 1917.

EDMUND C. MORGAN.
